United States Patent Office

Des. 233,982
Patented Dec. 24, 1974

233,982

BOTTLE

William E. De Graw, Modesto, Calif., assignor to E. & J. Gallo Winery, Modesto, Calif.

Filed May 9, 1973, Ser. No. 358,666

Term of patent 14 years

Int. Cl. D9—01

U.S. Cl. D9—148

FIG. 1 is a perspective view of a bottle showing my new design;

FIG. 2 is a top plan view thereof;

FIG. 3 is a side elevational view thereof; and

FIG. 4 is a bottom plan view thereof.

I claim:

The ornamental design for a bottle, substantially as shown and described.
